UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

TABULATING MECHANISM.

1,294,847.

Specification of Letters Patent. Patented Feb. 18, 1919.

Original application filed May 20, 1916, Serial No. 98,853. Divided and this application filed March 27, 1918. Serial No. 224,960.

To all whom it may concern:

Be it known that I, OTTO THIEME, a citizen of the United States, residing at St. Louis, Missouri, have invented a certain new and useful Improvement in Tabulating Mechanism, of which the following is a full, clear, and exact description, such as will enable others skilled in the art to which it appertains to make and use the same, reference being had to the accompanying drawings, forming part of this specification, in which—

Figure 1 is a rear elevational view of a part of a calculating machine equipped with my improved tabulating mechanism.

Fig. 2 is a horizontal sectional view through the same.

Fig. 3 is a rear elevational view of part of the tabulating mechanism.

Fig. 4 is a detail view of the automatic means for operating the tabulating mechanism from the bar carried by the typewriter carriage.

Fig. 5 is a side elevational view showing one of the typewriter carriage stops in section.

Fig. 6 is a side elevational view of the rear portion of the tabulating mechanism.

Fig. 7 is a side elevational view of an entire combined adding and typewriting machine with the rear frame walls broken away to illustrate certain of the parts identified with my present invention.

This invention relates to a new and useful improvement in tabulating mechanism for combined adding and typewriting machines of the Moon-Hopkins billing machine type, and is a division of an application filed by me May 20, 1916, Serial Number 98,853.

The parent case discloses a tally roll attachment for the Moon-Hopkins billing machine and as is well known, the Moon-Hopkins machine is a combined adding and typewriting machine in which there is ordinarily a paper carriage 1 for supporting a sheet of paper on which the words-printing mechanism of the typewriter may make printing impressions by the operation of the keys 2, in addition to the printing type 3 controlled by the adding mechanism to record items set up by the keys 4 and totals thereof. These items and totals are indicated by the registers wheels 119 and 268 which are operated

by the racks 100 which latter carry the type 55 3 at their forward ends. In the tally roll attachment, printing segments 561 are positioned by the racks so as to locate printing type 561 in the printing line, the printing impression being made by a platen 505 60 carried by a vibratable frame 503 laterally movable on a shaft 502 mounted in suitable brackets 501 secured to the casing or housing 500 which incloses the adding mechanism at the rear portion of the machine.

The frame 503 is pulled leftwardly by means of a spring 526 (or rightwardly as seen from the rear in Fig. 3), and said frame carries at its lower end a notched plate or escapement bar 521.

The escapement bar 521, carried by the frame 503, is provided with a series of recesses 521^a and projections 521^b located according to the desired stepping movement of the frame with which recesses and projections coöperates an escapement pawl 527 (see Fig. 3) in the form of a bell crank lever, said escapement pawl being pivoted to a bracket 530 extending inwardly from the track rail 520. This track rail is cut away 80 or recessed to permit the operation of the escapement pawl. The escapement pawl has a leaf spring member 527^a secured thereto and whose free rear end coöperates with the projections 521^b on the escapement rail, 85 the purpose of this spring 527^a being to absorb the shock of the tally-roll carriage.

531 represents a bar slotted at each end to engage screws which find a bearing in some suitable frame members of the machine 90 (see Fig. 4), whereby through the medium of these guiding slots, the bar 531 may be moved rearwardly into engagement with the escapement pawl to depress the rear end of the same out of the path of its coöoperating 95 projection 521^b on the escapement rail 521. Bar 531 is held forwardly by means of a spring 532. A tappet 533 is mounted upon the extreme forward end of the bar 531 to coöperate with adjustable blocks 534 mounted 100 upon the notched rail 39 of the typewriter carriage. These blocks 534 have pivoted members 535 mounted thereon. The front end of tappet 533 is beveled or inclined as shown in Fig. 4 so that as the typewriter carriage 105 moves leftwardly, in the direction of the arrow, on bar 39, the members 535 will engage the inclined end of the tappet 533 and

- cam the same rearwardly. Upon the return movement of the typewriter carriage to the right, the tappet 533 swings on its pivot in a manner well known without vibrating the bar 531. The tappet 533 is preferably operated during the tabulation movement of the typewriter carriage from one column position to another so that each of the tappets will be engaged, moved rearwardly, and 10 restored to its normal forward position before the typewriter carriage completes its tabulation movement. This is essential because if the adjustable block 534 were so positioned as to engage and hold its tappet 15 533 rearwardly at a time when the typewriter carriage was stationary, the escapement pawls controlled thereby would effect an incomplete operation, which is undesirable.
- 20 From the above, it will be observed that the tabulation of the tally roll paper carriage is controlled by the movement of the typewriter paper carriage and in positioning the blocks 535 on the latter, it is possible 25 to so adjust said blocks that the tally roll carriage will be tabulated only at a time when the typewriter paper carriage is moving, either in word printing operations, or in tabulating.
- 30 I have not in this application described any means for returning the tally-roll carriage, as this is disclosed in said parent case and forms the subject-matter of a companion divisional application filed by me of 35 even date herewith, Serial No. 224,961.
- What I claim is:
1. In an apparatus of the character described, the combination of a laterally movable paper carriage supporting paper to receive a printing impression from one set of type, a tally-roll paper carriage supporting paper to receive printing impressions from another set of type, a tabulating mechanism

for the latter carriage whereby the latter carriage may be successively moved to different positions for separate column printing, and means carried by the first mentioned carriage for operating the tabulating mechanism for the tally roll carriage.

2. In an apparatus of the character described, the combination of a laterally movable paper carriage for supporting paper to receive word and number printing impressions, a series of adjustable blocks thereon, a vibratable bar for coöperating with said blocks, a casing, a tally roll carriage supporting paper to receive printing impressions from a different set of printing type than those making impressions on the paper supported by the first mentioned carriage, said tally roll carriage being slidingly mounted relative to said casing, and tabulating mechanism for said tally roll carriage operable by said vibratable bar.

3. In an apparatus of the character described, the combination of a rock shaft, a tally-roll carriage slidingly mounted thereon, an escapement bar on said carriage, a vibrating pawl coöperating with said escapement bar, a shock-absorbing member carried by said pawl, and means for operating said pawl.

4. The combination of a notched bar carried by a laterally movable paper carriage, adjustable stops mounted thereon, a beveled tappet coöperating with said stops, a vibratable bar on which said tappet is mounted, an escapement pawl operated by said bar, and a tally-roll carriage having a notched bar coöperating with said escapement pawl whereby said tally-roll carriage may be released for movement at predetermined intervals as determined by said adjustable blocks.

In testimony whereof I hereunto affix my signature this 21st day of March, 1918.

OTTO THIEME.
